UNITED STATES PATENT OFFICE.

SIDNEY W. SINSHEIMER, OF DENVER, COLORADO.

FLUID-TREATING SYSTEM AND ELEMENT THEREOF FOR CENTRIFUGAL SEPARATORS.

1,209,216.

Specification of Letters Patent. Patented Dec. 19, 1916.

Application filed January 17, 1916. Serial No. 72,655.

To all whom it may concern:

Be it known that I, SIDNEY W. SINSHEIMER, a citizen of the United States, residing at the city and county of Denver and State of Colorado, have invented certain new and useful Improvements in Fluid-Treating Systems and Elements Thereof for Centrifugal Separators; and I do hereby declare the following to be a full, clear, and exact description of the invention, such as will enable others skilled in the art to which it appertains to make and use the same.

This invention relates to improvements in fluid treating systems, and elements thereof, for centrifugal separators.

The invention may be employed with any substance, centrifugally acted upon for separation purposes, wherein the substance is treated or sprayed with a fluid or liquid, chemically impregnated or otherwise, still the primary use for which I have designed the same particularly relates to the treating or washing of sugar, for freeing the same from molasses and impurities.

At the beginning, it may be stated, that throughout the specification and claims, in using the terms "air" under regulated pressure, and "treating fluid" or liquid, I do not limit myself to the specific use of air or water, employed in sugar washing, for any elastic fluid, such as gas, might be employed, or "treating fluids" or liquids, other than water might be used to advantage in the chemical treatment of certain substances, and it will be understood, therefore, that these terms used for simplicity, are intended to cover a full range of equivalents.

Also, it will be understood that the invention is not limited to the specific use mentioned, but as the structural arrangement and principles involved are always substantially the same, for the purpose of simplicity, I shall so illustrate and describe it as applied to a centrifugal sugar separator.

Generally speaking my invention consists of certain novel elements combined in a simplified system, for delivering a predetermined quantity of the treating fluid (such as water in sugar washing) to the contents of a centrifugal separator, the quantity of which fluid is automatically measured by a uniform measuring pot, provided with mechanical means which may be set for regulating the amount of delivery as predetermined, and which fluid is also delivered

under a regulated pressure, subject to change at will.

The primary object of the invention, therefore, is to set a measuring device to automatically regulate the delivery of the desired quantity of treating fluid, under a regulated pressure. 60

A second object is to provide a particular form of measuring receptacle or pot, which is of uniform size, and contains means which may be adjusted to any degree to measure a predetermined quantity of treating fluid, and regulate its delivery. 65

A further object is to provide an arrangement, whereby a local controlling device, occupying inconsequential space, may be installed at the place of use, near the centrifugals, while the supply tank and measuring pot may be remotely removed, which would probably be desirable in large plants. 70

A still further object is to avoid the use of flexible connections or couplings, such as hose pipe now commonly employed in similar relations, and to simply provide rotating metallic joints or couplings, for the main control, the measuring pot control, and the spray or delivery nozzles. 75

With these and other objects in view, the invention consists of certain novel elements and the structural arrangement and combination of parts, as will be more fully described in the following specification and particularly pointed out in the appended claims. 80

It will be obvious that the invention is not limited to the exact details as shown and described, nor to the specific use of sugar washing, still for the purpose of a complete disclosure, reference is had to the accompanying drawings illustrating a practical embodiment of the invention, in which drawings like characters designate the same parts in the several views, and in which— 85

Figure 1, is an assembled view of the salient elements of the system. Fig. 2, is a top plan view, partly in horizontal section on the line 2—2 of Fig. 3. Fig. 3, is an elevational view of the measuring pot, showing the operating handle and indicator for the adjustable branch feed pipe, and partly in vertical section showing the interior arrangement of said pot. Fig. 4, is a fragmentary plan view of the top of the sugar basket and its containing receptacle, and showing the mounting of the spraying nozzle. Fig. 5, is 100

a fragmentary detail view, in vertical section, of the same, showing the nozzle in full spraying position, and in dotted lines in the position where it starts to spray, and where it is entirely shut off. Fig. 6, is a front elevation of a pair of three-way valves, operated simultaneously by a single lever, and controlling respectively the air supply and the treating liquid supply. Fig. 7, is a side 10 elevational view of the air valve arrangement, looking at the same in the direction of the arrow 7 in Fig. 6. Fig. 8, is a sectional detail view, of the liquid cock thrown to a position opposite to that shown in Figs. 15 6 and 7, and with communication open between the supply tank and the measuring pot, and Fig. 9, is a similar view of the air cock, set with communication open between the top of the measuring pot and the relief pipe.

20 Describing my invention in detail, with reference to a sugar separator, although not so limited in use as heretofore stated, 1 designates the usual outer receptacle for receiving the thrown off molasses and water, and 25 which is provided with a discharge outlet, not shown.

2 is a flanged annulus, disposed internally of the outer receptacle, and recessed to receive a flat ring 3, on which is fixed a bearing support 4 for mounting the spraying nozzle 5 communicating with the liquid treating pipe line, through a rotary valve connection, not shown in detail, but indicated at 6, the position of the nozzle 5 in 35 full operative position being shown in full lines in Figs. 1, 4 and 5, and in Fig. 5 it is shown dotted, in substantially horizontal position to begin spraying, and in vertical position, where the flow is completely shut 40 off. The opening and closing of the nozzle valve is controlled by the swing of the nozzle.

7, designates the sugar basket, which is of the usual type, having an upwardly flaring 45 internal top flange 8, and a foraminous or reticulated cylindrical wall 9, through which the molasses and water are thrown into the receptacle 1 by centrifugal force, as the basket is rapidly rotated on a vertical axis.

50 10 indicates the sugar line.

In Fig. 1, the centrifugal separator is simply shown conventionally, but of course it is provided with an internal rotary basket as in Fig. 7.

55 These parts in themselves form no essential novel feature of the invention, although it is beneficial to have a rotary mechanical coupling, including a control valve, between the nozzle and the pipe line, instead of employing a hose pipe connection as is customarily done.

Referring now to Figs. 2 and 3, which illustrate in detail the principal essential feature of the system, 11 designates a container, which I refer to as the "measuring

pot", provided with a closed lid 12, securely bolted thereon, and may have a drainage tap 13 at the bottom to remove accumulated sediment. This container has the bosses 14 and 15, oppositely disposed, on its outer surface, 70 which together with the wall of the container are tapped as at 16, to receive and rotatably support a horizontally disposed pipe 17 within the container. The boss 14 is further tapped or drilled to receive a suitable packing 18 and the stuffing box or gland 19, the latter having a flanged head or plate 20 through the medium of which the gland is held up against the packing by the stud bolts 21. The tap of the boss 15 may be provided with a plug 22, to take up the end thrust of the pipe 17, and also close the outlet to prevent leakage from the container, the end of the pipe itself being plugged or otherwise capped or closed.

85 The pipe 17 is formed of two sections, connected by a T-coupling 23, in the third opening of which is threaded a vertically swinging branch feed pipe 24, varied positions of this feed pipe being shown in full and dotted lines in Fig. 3, the purpose of which will be hereinafter fully referred to. In order to adjust this branch feed pipe 24 to any desired position in the container or measuring pot, I provide an operating handle 25, affixed to the protruding portion of the pipe 17, which latter terminates in a fluid tight rotary connection with the elbow joint 26, leading to the liquid pipe line hereinafter referred to.

90 Secured to the inner face of the flange head 20, by the rivets or screws 27, is a scaled segment plate 28, with which cooperates a pointer or indicator finger 29, carried by a sleeve 30, fixed to the pipe 17 to rotate therewith and indicate the measured amount of liquid, say for instance in gallons, to be discharged, dependent upon the position or angle at which the branch pipe 24 is disposed in the measuring pot.

105 Referring now to Fig. 1, 31 designates the supply tank or source of supply for the treating liquid, and 32 the inlet thereto, which may be controlled by a float operated valve arrangement 33. 34 is a compressed air tank or source of compressed air supply, and 35 shows conventionally an air pressure regulator, of any suitable type, to control the degree of pressure at which the air is delivered to the measuring pot. At 36 I have shown a supporting plate or shelf between a pair of separators, which is conveniently located, but which is merely shown by way of illustration. Above the support 110 36 is mounted a pair of three-way valves 37 and 38. This pair of valves is operated by a single lever 39, which when thrown in the position shown in Figs. 6 and 7, opens communication between one set of ports with the 115 pipe lines, to open communication between 30

the compressed air tank and the top of the measuring pot, and between the liquid in the measuring pot and the spray nozzles, to permit of spraying under regulated pressure; and when thrown in the opposite direction, opens communication between the supply tank and the measuring pot, and also from the top of the measuring pot to the atmosphere. These valves 37 and 38 may be referred to, respectively, as the air and the liquid control valves. Each comprises a casting, provided with a rotary plug having, respectively, the communicating ports 39, 40 and 41, of the air valve, and 42, 43 and 44, of the liquid valve. The air valve casing 37 has the central branch 45, and the end branches 46 and 47, while the liquid valve casing has similar branches 48, 49 and 50, which connect with their complementary pipes of the system, designated by the same numerals.

To now trace out the lines of piping:— The cover 12 of the measuring pot is tapped centrally at 51, and from this tap a pipe 46 leads directly to one branch of the air valve; from the central branch of the air valve 37, a pipe 45 leads to the air pressure regulator 35; and from the third branch of the valve, the pipe 47 leads up to the liquid supply tank and terminates just above the liquid line therein. From the elbow 26 of the trunnioned pipe 17, the pipe 50 leads to the rear end or branch of the liquid valve 38; the pipe 49 leads from the other end branch 35 of the valve 38 to the spray nozzles 5; while the pipe 48 leads from the supply tank 31 to the central branch of the valve casing 38.

From the foregoing complete description, it is believed that the advantages and operation of my invention will be fairly understood, but it might be said that, the measured quantity of treating liquid having been delivered, as shown in Fig. 3, where the level of the treating liquid has reached a position incident with the lowered position of the normally submerged end of the branch feed pipe 24, the measuring pot is now to be refilled against the pressure of the head of air in the pot above the water or treating fluid. The valve lever 39^a is then thrown to the left, when the three-way valves will move through an angle of forty five degrees into the positions shown in Figs. 8 and 9, whereupon the air in the measuring pot escapes through the pipe 46, across the valve 37, through the ports 39 and 40, to the pipe 47, and is discharged above the liquid in the supply tank 31. At the same time the supply tank delivers its liquid through the pipe 48, the ports 43 and 44, of the valve 38, to the pipe 50, and thence to the measuring pot. In reversing the lever 39^a, by throwing it to the right as in Figs. 1, 6 and 7, the positions of the valves are reversed, and the compressed air from

the tank 34 (the degree of pressure being controlled at 35) passes through the pipe 45, the ports 39 and 41 of the air valve 37, through the pipe 46, into the head of the measuring pot at 51, directing the air pressure against the volume of liquid in the measuring pot, from whence the liquid is forced, under this regulated pressure, through the branch feed pipe 24, the rotary pipe 17, the pipe 50, the ports 43 and 42, of the liquid valve 38, into the pipe 49, leading to the spraying nozzles 5, which latter when swung downwardly into proper position direct the discharge against the inner surface of the mass or substance, in the baskets 7, the liquid and molasses, in the washing of sugar, being thrown outwardly through the reticulated cylindrical call 8 of the baskets into the outer container 1, and when the level of the liquid reaches the lower end of the pipe 24 and the spraying is thereby discontinued, the volume of compressed air may be utilized, if desired, to act as a drying agent for the mass, until the operation is completed, when the resultant sugar may be extracted and a new charge inserted for treatment.

It will be observed that by operating the handle 25 the branch feed pipe can be set at any angle, to supply a predetermined measured amount of the liquid, as the liquid will only be forced therethrough while the end of the pipe 24 remains below the surface of the same. The graduations on the indicator segment will be so computed that the position of the pointer will indicate the number of gallons or other units of measure that will be discharged, owing to the position of the feed pipe in the measuring pot.

It may also be observed that by having a central or main control at the three-way valves, and a local control at the nozzles, my system is not limited to a single separator, but any number of separators may be coupled up in the system, two being shown in Fig. 1, and only one measuring pot and one supply tank will be necessary. Thus one centrifugal can be operating, while another is being unloaded, and still another loaded for treatment, and hence considerable loss of time is avoided.

The particular arrangement of the air and liquid three-way valves as shown, is merely by way of illustration, and the connection of the piping therewith might be accomplished with similar results in any other suitable way.

It may be that, in some prior systems, means have been devised to shut off the flow of the treating liquid by a timing device, motor controlled or otherwise, which timing device is actually moved gradually while the liquid is flowing, such for instance as a shut-off plug cock, so that in that sense the extent of discharge is controlled; but such

devices are manifestly not entirely satisfactory and have proven positively inaccurate in practice, and my claims are not directed to any such arrangement, nor to any arrangement wherein the delivery might be partially but ineffectively controlled for instance by a free piston operating in a measuring cylinder. I am not aware, however, of any prior systems of this character, in which 5 the same predetermined or measured quantity of discharge may be successively delivered, without resetting the measuring control element, excepting for the purpose of varying the desired quantity of discharge, as 10 is accomplished by my measuring pot arrangement, operating in conjunction with other essential elements of the combination, which are inseparable features of the improved system, substantially as described. 15 Nor am I aware of such a system even, whereby a charge of the treating fluid is delivered by the action of a pressure fluid, the degree of pressure being preferably regulated at will, the said pressure fluid being 20 under positive mechanical control to turn on or shut off the same, and simultaneously to, respectively, permit of a measured discharge from, or the refilling of the measuring receptacle, independently of any pressure operated check valves or pistons in the system, 25 which are always more or less unsatisfactory and liable to become inoperative from various causes.

Therefore, what I do claim as new, is:—

30 1. In a system substantially as set forth, including a treating fluid source, a receptacle for receiving and delivering the treating fluid, and a delivery nozzle, in combination with a source of operating pressure fluid, 35 adapted to co-act with the treating fluid in said receptacle; conduits extending from the said nozzle, the said pressure fluid source, and the said treating fluid source, and communicating respectively with said receptacle; and controlling means, common to all of

said conduits, and including valve elements functioning to positively open and close said conduits, regardless of the pressure of said fluids, in the relative relations set forth, substantially as described. 50

2. In a system substantially as set forth, including a treating fluid source, a receptacle for receiving and delivering the treating fluid, and a delivery nozzle, in combination with a source of operating pressure fluid, 5 adapted to co-act with the treating fluid in said receptacle; conduits extending from the said nozzle, the said pressure fluid source, and the said treating fluid source, and communicating respectively with said receptacle; controlling means, common to all of said conduits, including valve elements functioning, regardless of the pressure of said fluids, to positively open and close said conduits in the relative relations set forth; and a pressure regulator, operable at will, disposed in the line of said pressure fluid conduit, substantially as described.

3. In a system substantially as set forth, including a treating fluid source, a delivery nozzle, a measuring pot, and conduits leading from said measuring pot to said treating fluid source and said nozzle, respectively, in combination with a measure regulating element, comprising a movably mounted feed tube, in communication with said conduits, adjustable to variable fixed positions in said pot for the purposes set forth, a source of operating pressure fluid, adapted to co-act with the treating fluid in said pot through a communicating conduit, and controlling means, common to all of said conduits, and including valve elements positively functioning to open and close said conduits in unison, regardless of the pressure of said fluids, in the relative relations set forth, substantially as described. 8

In testimony whereof, I affix my signature.

SIDNEY W. SINSHEIMER.
